MODULATING RELAYS

Roger Pierre Dubusc, Saint-Cloud, France, assignor to Compagnie Pour la Fabrication des Compteurs et Matériel d'Usines à Gaz, Montrouge-Seine, France, a corporation of France

Application June 17, 1958, Serial No. 742,674

9 Claims. (Cl. 200—87)

The present invention relates to modulating relays. It is well known in the art of modulating relays of the electro-mechanical type that excitation by an alternating voltage of a known value and frequency may activate a group of associated contacts which may open and close in a fixed relationship with the phase of the excitation voltage.

Conventionally, the armature is constructed of soft iron, movably enclosed, and magnetized by an electrical winding which may be polarized by a magnet. The free extremity of the armature may contain an insulated member which actuates a group of contacts which is of thin resilient construction and has at its extremities, contact disks of various metallic composition or noble alloys of such composition to reduce or minimize oxidation.

One particular known construction utilizes a complex oscillating system containing two or more elements which may be mechanically coupled to other associated elements and subjected individually to magnetic or mechanical forces; and certain of these forces tend to restore the elements to the median position, while certain other forces tend to move the elements in an opposing manner. The overall equilibrium of the system depends, in addition to these forces, on other differential parameters which individually must be very constant in order that the system be stable.

The improvements forming the present invention have as their primary object substantially obviated these difficulties. They have the further objective of permitting the realization of a modulating relay of simple and economical construction and of great stability of operation.

These improvements are characterized in that the motor armature element is aperiodic and can oscillate at the frequency of the voltage of excitation without superimposing any direct extraneous forces on the motor armature element. In other words, the mean position of the oscillatory element is indeterminate in a certain zone of its movement.

In accordance with one embodiment of the invention, the aperiodic motor armature element is made up of a metallic armature framework forming a ring in short circuit which can oscillate inside two arcuate openings in a magnetically polarized circuit formed by the alternating field produced by a winding connected to the terminals of the voltage of excitation. This alternating field extends into the interior of the armature framework and is perpendicular to the magnetic field of polarization. At the lower end of the spindle of the armature framework is affixed a support member, having at one end thereof an insulating finger which is positioned between two contact members, such as thin spring leaves or wires. Between these contact members there is placed likewise a fixed block contact. When the dimension or diameter of the block contact is greater than that of the insulating finger, the contacts are closed at rest; conversely, when the dimension or diameter of the contact block is smaller than that of the insulating finger, the contacts are open at rest. Advantageously, the thin spring leaves or wires

2

are positioned in parallel relationship. These contact members are preferably adjusted to exert at rest substantially the same forces of pressure and movement on the fixed block contacts, such that the dynamic movements of the elements of this system are brought back by forces equal and opposite to the position of the elements when deviation occurs in one direction or another. The oscillatory movement of the system is thus symmetrical with regard to the mean position of the contact members, wherein it will be appreciated that the duration of contact closure is the same for each of the contact members.

The present invention will be better understood from the description which follows and the drawings attached thereto, which description and drawings are given as merely illustrative and without limitation of the uses to which the invention may be applied.

Figure 1 represents in vertical cross section one embodiment of the invention.

Figures 2 and 3 are horizontal cross sections of the embodiment of Figure 1, taken along lines 2—2 and 3—3, respectively.

Referring to the figures, numeral 10 represents a magnetic circuit structure comprised of a group of laminated iron plates or other magnetic materials, such as ferrites, defining two semi-circular arcuate openings 11 and 11'. This magnetic circuit structure is composed of two parts, an outer laminated core 12 containing an interior cavity and an inner laminated core 13 of rectangular form, having at its center portion an enlargement of circular form whose edges define one of the sides of the arcuate openings 11 and 11'. The inner core 13 is formed in its center area with an aperture 14, wherein passes freely the spindle or shaft 15 on which is fixed the armature framework 16. In one part of the cavity of the outer core 12 there is positioned two permanent magnets 17 and 17' of parallelepipedal form and magnetized as indicated on Figure 2.

One surface of each magnet is concave and circular, thus defining respectively the other side of the arcuate openings 11 and 11', at the interior of which the armature framework 16 can be displaced. Lateral to the inner core 13 and at the interior of the cavity of the outer core 12 are positioned two electrically energizable windings or coils provided with terminals to be connected to a source of alternating current. These windings, 18 and 18', produce an alternating field whose lines of force in the inner core 13 are perpendicular to the field produced by the permanent magnets 17 and 17', respectively. The magnetic circuit structure 10 and the windings 18 and 18' are kept in position by two magnetic supports 19 and 19' of soft iron, completing the magnetic circuit which is encased by two cylindrical rivets 20 and 20', having sleeve members 21, 22, 23, 24, respectively, positioned around the extremities thereof. The magnetic supports 19 and 19' are provided with bearing mount openings in the centers thereof. These mount openings are two bearings 25 and 25' which cooperate with the end pins of the spindle 15. On the lower part of the spindle 15 is affixed a support member 27.

In the illustrative example, one end of the support member 27 carries an insulating finger 28. The finger 28 is positioned between the two leaf contact members 29 and 29', which advantageously may be rectilinear and parallel, as shown. These contact members 29 and 29' are affixed to two contact supports 30 and 30', respectively, which are mounted on the terminals 31 and 31' of the base plate 33 in a manner analogous to that utilized in vacuum tubes. Between the contact members 29 and 29', a contact block 32 is positioned. This contact block 32 is affixed to another terminal positioned on the base plate 33. A housing 34, constructed of soft iron, is welded to the base plate 33.

The magnetic circuit structure, the moving armature framework assembly and the arrangement of the contacts are hermetically and magnetically sealed within the housing 34. This housing 34 may be filled with an inert gas, such as nitrogen, if desired. Hence, the making and breaking of the contacts between the contact members 29 and 29' on one part, and the fixed contact block 32 on another part during the oscillatory movement of insulating finger 28 occurs without oxidation of the contact surfaces, which permits their proper functioning over long operating periods of time.

This unique construction provides a system wherein the entire elements of the modulating relay are hermetically sealed. This consideration is due to the fact that the motor armature unit utilized in the present invention is in a state of rest and devoid of any counter-acting resilient forces. In addition, this complex oscillating system utilizes a moving armature framework without the use of guide members which are generally used in conventional vibratory chopper-like systems. Furthermore, the contact assembly of the present invention exhibits extremely low contact potential voltage, is perfectly balanced and stable and requires no further outside adjustment or external control.

The modulating relay of the oscillatory type of the present invention further provides the unique construction wherein fatigue of the contact members is substantially absent, as characterized by the conventional vibratory systems of the prior art. Furthermore, this system may operate at extremely high chopper frequencies, including a few thousands of cycles per second, and still being capable of chopping very small values of direct current when being subjected to extremely high gravitational forces experienced in aircraft and missile use.

I claim:

1. A modulating relay comprising in combination a hollow housing, an electromagnetic oscillator positioned within said housing, said oscillator including a laminated iron core defining a pair of opposed central cavities, a permanent magnet extending through each of said cavities, a pair of spaced electrically energizable coils positioned within said cavities adjacent the magnets, said magnets, said coils, and said laminated core defining a pair of elongated arcuate apertures at the center of said core, a closed loop armature having a first pair of opposed arms positioned in said arcuate apertures and a second pair of opposed arms secured to a rotatable spindle extending through the center of said core such that such armature is caused to oscillate within said arcuate apertures in response to the energization of said coils, and electrical contact members connected to said spindle and adapted to be actuated in response to the oscillation of said armature and said spindle.

2. A modulating relay comprising in combination an electromagnetic oscillator including a laminated iron core defining a pair of opposed central cavities, magnet means extending through each of said cavities, a plurality of spaced-apart electrically energizable coils positioned within said cavities adjacent the magnet means, said magnet means, said coils and said laminated core defining a pair of apertures at the center of said core, a closed loop armature secured to a rotatable spindle extending through the center of said core such that such armature is caused to oscillate within said pair of apertures in response to the energization of said coils, and electrical contact members connected to said spindle and adapted to be actuated in response to the oscillation of said armature and said spindle.

3. A modulating relay comprising an electromagnetic oscillator including a laminated iron core defining a pair of opposed central cavities, a pair of spaced-apart electrically energizable coils positioned within said cavities, a permanent magnet in each cavity between said pair of coils, said magnets, said coils, and said laminated core defining a pair of elongated apertures at the

center of said core, a closed loop armature having a first pair of opposed arms positioned in said elongated apertures and a second pair of opposed arms secured to a rotatable spindle extending through the center of said core such that such armature is caused to oscillate within said elongated apertures in response to the energization of said coils, an actuating member of insulating material secured to said spindle for oscillation therewith, and a plurality of electrical contacts adapted to be actuated by said member in response to the oscillation of said armature and spindle upon energization of said coils.

4. A modulating relay in accordance with claim 1 wherein said electrical contacts comprise a pair of parallel, spaced apart, resilient fingers and a fixed metallic contact positioned between said fingers and adapted for alternate contact therewith in accordance with the oscillation of said actuating member.

5. A modulating relay comprising in combination a hollow housing, an electromagnetic oscillator positioned within said housing, said oscillator including a laminated iron core, a pair of spaced-apart, permanent magnets and a pair of spaced-apart electrically energizable coils, said magnets, said coils and said laminated core defining a pair of elongated arcuate apertures at the center of said core, a closed loop armature having a first pair of opposed arms positioned in said arcuate apertures and a second pair of opposed arms secured to a rotatable spindle extending through the center of said core such that such armature is caused to oscillate within said arcuate apertures in response to the energization of said coils, electrical contact members associated with said spindle and adapted to be actuated in response to the oscillation of said armature and said spindle, and an electrical terminal connected to each contact member and extending outside of said housing for connection to a utilization device controlled by said modulating relay.

6. A modulating relay comprising the improvement of a first group of laminated iron plates, each formed with a central opening to define an interior cavity, a second group of laminated iron plates positioned within said interior cavity, a pair of spaced apart, electrically energizable coils positioned around the second group of laminated iron plates, a pair of magnets between said coils and adjacent opposite surfaces of said second group of laminated iron plates, said magnets and said opposite surfaces being spaced from each other to define a pair of opposed arcuate openings, a spindle rotatably positioned in an aperture extending through the center of said second group of laminated iron plates, a plurality of contacts disposed at one end of said spindle and adapted to be actuated by the rotation of said spindle, and a rotatable armature fixed to said spindle for oscillation in said arcuate openings in response to the energization of said coils, said rotatable armature comprising a closed metallic loop having portions positioned within said opposed armature openings and other portions secured to said spindle.

7. A modulating relay comprising a fully enclosed hollow housing having positioned therewithin a first group of laminated iron plates, each formed with a central opening to define an interior cavity, a second group of laminated iron plates positioned within said interior cavity, a pair of spaced-apart electrically energizable coils positioned around the second group of laminated iron plates, a pair of magnets between said coils and adjacent opposite surfaces of said second group of laminated iron plates, said magnets and said opposite surfaces being spaced from each other to define a pair of opposed arcuate openings, a spindle rotatably positioned in an aperture extending through the center of said second group of laminated iron plates, and a rotatable armature fixed to said spindle for oscillation in said arcuate openings in response to the energization of said coils.

8. A modulating relay in accordance with claim 5 wherein said rotatable armature comprises a closed metallic loop having portions positioned within said opposed

armature openings and other portions secured to said spindle.

9. A modulating relay in accordance with claim 6 further comprising a plurality of contacts disposed at one end of said spindle and adapted to be actuated by the 5 rotation of said spindle and said armature.
